UNITED STATES PATENT OFFICE

GUSTAVUS W. ESCHENBACH, OF LOS ANGELES, CALIFORNIA

PICTORIAL DISPLAY APPARATUS

Application filed March 28, 1931. Serial No. 526,033.

This invention relates to a pictorial display apparatus of the general character of that shown in my United States Patent 1,728,402, patented September 17, 1929.

5 The object of the invention is to improve pictorial display apparatus particularly in the arrangement of the means for providing the illumination, and in the combination thereof with means for mounting the pictorial displays that are to be illuminated.

One feature of this invention consists in mounting electric lamps in fixed connection with revolvable display cylinders and independently of the shaft on which the cylinders are frictionally mounted, a means for supplying electric current to the lamps at all times during the revolution of the cylinders. Another feature of the invention consists in providing terminal members in each 20 side of each cylinder which register and contact with the terminal members of the adjacent cylinders, so the current will be passed through the various cylinders to the lamps therein, whereby the lamps may be varied in colors and the cylinders may be given varied 25 degrees of rotation and yet the lamps be constantly illuminated. Another feature of this invention consists in adapting the machine to the use of neon lighting in connection 30 with said electric lamp lighting or independently thereof.

The full nature of this invention will be understood from the accompanying drawings and the following description and claims:

35 Fig. 1 is a central vertical section through the apparatus, a portion of each end being broken away. Fig. 2 is a perspective view of the stationary terminal member shown at the left hand end of Fig. 1, a part thereof being broken away. Fig. 3 is a transverse section 40 on the line 3—3 of Fig. 1 showing the left side of one of the cylinders. Fig. 4 is a plan view of adjacent terminal blocks, parts being broken away or omitted. Fig. 5 is a side elevation of the right hand terminal member in Fig. 4. Fig. 6 is a front elevation of the apparatus with the driving mechanism omitted. Fig. 7 is a section on the line 45 7—7 of Fig. 6. Fig. 8 is a plan view of two adjacent terminal members and

associated parts partly broken away. Fig. 9 is a vertical section of one of the terminal members and a shaft, the shaft, however, being broken away as indicated. Fig. 10 is a perspective view of a lamp bracket. Fig. 11 is a central vertical section of a part of an apparatus showing a modified form of the invention adapted for using neon lighting and the like in addition to the incandescent lighting, or employing either of said means of illumination, parts being broken away and parts omitted. Fig. 12 is an elevation of the inner side of the stationary terminal member showing the shaft in section. Fig. 13 is a similar view of the right hand side of the 65 terminal member at the right hand side of one of the cylinders, the said shaft being in section on the line 13—13 of Fig. 11.

Fig. 14 is a plan view of a part of one of the cylinders, remaining portions being broken away. Fig. 15 is a section of a cylinder on the line 15—15 of Fig. 11, a part being broken away. Fig. 16 is an elevation of the terminal member in the left hand side of each cylinder.

In this apparatus there is a central rotatable shaft 10 horizontally disposed preferably with one end mounted in a frame member 11, but the means for mounting the other end and the means for driving it are not shown, as they constitute no necessary part of the present invention. On this shaft there are mounted a plurality of pictorial display cylinders, six of them as shown in Fig. 6. Each cylinder is composed of two end walls 12 hexagonal in form, as shown here, and connected by a plurality of longitudinally extending lamp brackets 13, and on the periphery of each end wall 12 there are corner pieces 111, adapted to receive removable pictorial glass plates 14, as desired. In each of the pictorial cylinders here shown there are six lamp brackets 13 and each lamp bracket has turned-up ends 15, secured by screws 16 through holes 17 to the end walls 12 of the cylinder. On each lamp bracket 13 there is an electric lamp 19 removably mounted in lamp socket 18.

The six pictorial cylinders are frictionally mounted on the shaft 10 by means shown in 100

Fig. 9, so that said cylinders will normally rotate with the shaft. This movement is ordinarily a slow movement, but the frictional mounting of the cylinders permits any cylinder to be manually or otherwise independently turned to any desired extent in order to adjust the cylinders to present the pictures therein as desired.

Means for frictionally holding the cylinders on the shaft, as shown in Fig. 9 herein, consists of a set screw 20, threaded into one of the terminal blocks 21, surrounding the shaft and centrally mounted in the side wall of the cylinder. Said screw 20 forces a friction head 22 against the shaft 10 through the intervention of an intermediate spiral spring 23. By changing the screw, the pressure of the friction head 21 on the shaft can be increased or diminished as desired.

There is a terminal member or block 21 in each end wall 12 of each cylinder, as seen in Fig. 1, and on each of said terminal blocks there is secured a series of angle irons 25, as indicated in Figs. 1, 3, 5 and 7, with which the bent ends of the bracket 13 engage and through which the screws 16 extend so that the side wall 12 is rigidly mounted on the terminal block 21 and rigidly connected by the bracket 13 with the terminal block and side wall 12 on the other side of the cylinder, thus constituting a rigid unit.

The terminal block 21 in the left hand side of each cylinder, as seen in Fig. 3, has a series of segmental metal positive plates 30 and a corresponding series of segmental negative plates 31 in pairs, secured thereto, there being a pair of these plates for each lamp in each cylinder. Therefore, there are six of said segments, as shown in Fig. 3, in each series.

From each of the positive segments 30 a positive wire 32 leads to the lamp and from the lamp a negative wire 33 leads to the negative segments 31 and from those wires 32 and 33 corresponding wires lead to the spring pressed brushes 34 in the opposite terminal block of each cylinder, as seen in Figs. 4 and 5, and said brushes extend through corresponding contact plates 130 on said terminal block 21 as best shown in Figs. 4 and 5. The terminal plates 130 on one side of the cylinder register with the terminal plates 30 on the other side of the cylinder so that the brushes engage said plates. The same arrangement is made with reference to the negative brushes 134 and negative terminals 131. Thus the positive and negative terminal plates are concentric on the sides of all the cylinders.

At the left hand end of Fig. 1 there is secured a stationary terminal block 40, similar to the other terminal blocks and having similar positive segmental plates 230 and positive negative plates 231. On the two segments of these plates 230 and 231 are provided

brushes 34 and 134 and the remainder of the segmental plates 234 are dead. A positive line 41 comes from a suitable source of electricity to binding post 42 and a connection 43 therefrom extends to each brush in the stationary block 40. The negative current passes from the negative brushes through the connection 44, binding post 45, and negative line 46, as shown in Fig. 1.

As appears in Fig. 1, therefore, the electric lamps of each longitudinal row are connected in series with the positive line and also with the negative line and as the shaft rotates, current illuminates said lamps in two rows, preferably the two front rows, and the remaining lamps are dark. This is controlled by the stationary terminal block 40 shown in Fig. 2 which has only two sets of segments adapted to transmit current and they are at the front of the machine. The number of rows of lamps to be simultaneously illuminated may be changed as desired.

The cylinders can be independently turned and each has its own path, being separated from the other cylinders by pins 50, as seen in Figs. 1, 4 and 5, but as each is individually turned, or adjusted relative to any other cylinder, the lamp lighting connections are maintained. By changing the color as by using colored lamps, quite a varied lighting effect can thus be produced. If one pictorial cylinder is independently retarded or accelerated, its positive terminals would change relative positions with the corresponding terminals on the adjusting cylinders or in the stationary terminal block 40.

From the foregoing it will be understood that as the shaft and pictorial cylinders rotate, there is a supply of current through the two front rows of lamps 19 for a short period of time and as the rotation thereof proceeds one of said rows of lamps goes out and another row comes in, so that there is a constant procession of the rows of lamps, but at least two rows of lamps are illuminated all the time in the form herein shown. If one pictorial cylinder is independently retarded or accelerated the lamps in the illuminated row would thereby be changed. By employing different colors of lamp globes, the illumination would be changed mechanically and constantly and in any desired order or arrangement of colors.

The modified form of the invention shown in Figs. 11-16 makes no change in the illumination of the incandescent lamps, but it adds an additional means of illumination, properly termed "neon lighting".

There the stationary terminal block or member 75 is employed, it being similar to the block 40 shown in Fig. 2, excepting that it has four circular rows of terminals instead of two. The two inner rows are the same as shown in Fig. 2 and control the illumination with the incandescent lamps in the

same manner as hereinbefore explained. There is provided an outer series of segmental plates 76, two of them provided with brushes 77 and supplied with positive current through the line 78, binding post 79, and arm 80. There are two sections of negative terminals including the plates 81 and brushes 82 that are connected with the negative line 83, arm 183 and contact 283. These lines are controlled by switch 94.

10 The terminal block 85 in the left hand wall of each cylinder has similar terminal plates to those shown in Fig. 3, excepting that there are four concentric series of plates as seen in Fig. 16 and are contacted by the brushes in the adjacent terminal block.

15 The terminal block in the right hand end of each cylinder, shown in Fig. 13, is similar to that shown in Fig. 5, excepting that they have two additional rows of contact plates 87 and 88, concentric with the remaining contact plates, and closing the circuit to the neon lighting means, as shown in Fig. 13. All the series of segments extend entirely around the face of the terminal block.

20 Each pictorial cylinder has in each section thereof, as shown in Figs. 14 and 15, a neon unit 90 extending across the cylinder as seen in Fig. 14 and a glass 14 containing the pictorial matter extends to said neon unit, substantially as shown. Each neon unit is connected with the source of positive electricity by a line 91 and there is a negative line 92 extending to the corresponding segments in the terminal block in the side of the cylinder as illustrated in Fig. 15. The neon tube 93 may be formed in any design, that shown in Fig. 14 showing the word "Neon", but the word or design of said neon tube is preferably related to the pictorial subject matter below it, on each section of the cylinder.

25 There is a switch 84 controlling the current to the lamps and a switch 94 controlling the current to the neon light unit as shown in Fig. 11. Therefore, if both switches 84 and 94 are closed, both the incandescent lamps and neon tubes in two sections of the cylinders will be illuminated, and any desired change in what is shown may be effected by 30 annularly adjusting any cylinder on the shaft 10 or all of them. If switch 84 is closed, and 94 open, only lamp illumination results. If switch 94 is closed and 84 open, only neon lighting will result.

35 In Fig. 11 a slight change in the arrangement of the wires to the lamp circuit is made for the purpose of illustration. Current over wire 41 is connected to contact 42 connected by wire 43 to arm 143 arranged to supply current to the brushes 34. Another arm 100 is arranged to take the current off the brushes 134 and through wire 44 delivers it to the contact 45 on the switch 84 to the negative wire 46.

40 In operation the shaft 10 is driven to ro-

tate the cylinders, which rotation will move the parts as described to light the rows of lamps 19 intermittently and when the cylinders are equipped with the neon tubes 93 and rotated as stated they, as well as the 70 lamps, are lighted.

I claim as my invention:

1. Pictorial display apparatus, including a shaft, a plurality of individual pictorial cylinders mounted thereon so as to be independently revolved, illuminating means mounted in each cylinder, and means in each cylinder registering with corresponding means in adjacent cylinders for maintaining such illumination in a plurality of cylinders from a single source of electricity. 75

2. Pictorial display apparatus including a shaft, a plurality of individual pictorial cylinders frictionally mounted thereon so as to revolve therewith or be independently revolved as desired, illuminating means mounted in each cylinder, and electric terminals in each end of each cylinder electrically connected with said illuminating means and registering with and engaging corresponding terminals in adjacent cylinders for supplying current to said illuminating means. 80

3. Pictorial display apparatus, including a shaft, a plurality of individual pictorial cylinders mounted thereon so as to be independently revolved, illuminating means mounted in each cylinder and revoluble therewith around said shaft, and positive and negative electric terminals mounted in each cylinder and revoluble therewith about the shaft, said positive terminals being arranged in segments concentric with the axis of the shaft and each positive electric segment being electrically connected with its corresponding individual illuminating means in each cylinder. 90

4. Pictorial display apparatus, including a shaft, a plurality of individual pictorial cylinders mounted side by side on said shaft so as to be independently revolved, a plurality of illuminating means mounted in each cylinder and in annular series, an electric terminal in each end of each cylinder having separate positive segments in annular series, and electrical connection between each positive segment of the terminal and its corresponding illuminating means in said cylinders. 100

5. Pictorial display apparatus, including a shaft, a plurality of individual pictorial cylinders mounted side by side on said shaft so as to be independently revolved, a plurality of illuminating means mounted in each cylinder and in annular series, an electric terminal in each end of each cylinder having separate positive segments in annular series, electrical connections between each positive segment of the terminal and its corresponding illuminating means in said cylinder, with the terminals in the end of each cylinder fric- 115

tionally engaging correspondingly located terminals in the adjacent cylinder, whereby a longitudinal row of illuminating means would be simultaneously illuminated and each cylinder can be independently rotated to bring into such row the desired illuminating means in any cylinder.

6. Pictorial display apparatus, including a shaft, a plurality of individual pictorial cylinders mounted thereon so as to be independently revolved, an annular series of illuminating means mounted in each cylinder and revoluble with the cylinder, a terminal member having an annular series of positive segmental terminals and a negative annular terminal mounted in each end of each cylinder concentric with the shaft, a positive line running from each illuminating means to a positive segment, a negative line running therefrom to the negative terminal, and a stationary terminal member surrounding the shaft adjacent to the terminal member in a cylinder and having similarly formed electric terminals therein that are frictionally engaged by the terminals in the cylinder, and means for supplying current to the positive terminal segments.

7. Pictorial display apparatus, including a rotary shaft, a pictorial cylinder frictionally mounted thereon consisting of two end walls with means in their peripheries to receive pictorial illustrations, a plurality of lamp brackets secured at each end to the walls of said cylinder in a series surrounding said shaft, a lamp mounted on each bracket, a terminal member surrounding the shaft and secured in an end wall of the cylinder, an annular negative terminal in said terminal member connected with the negative side of the lamps, a series of segmental terminals in said terminal member concentric therewith, each of said segments connected with the positive side of said lamp, a corresponding stationary terminal member surrounding the shaft adjacent said terminal member in the cylinder and with similar terminals therein as are in the terminal member in said cylinder, and means for supplying current with said series of segmental terminals.

8. Pictorial display apparatus, including a rotary shaft, a plurality of individual pictorial cylinders frictionally mounted thereon, each cylinder consisting of two end walls with means in their margins to receive pictorial illustrations, a plurality of lamp brackets secured at each end to the walls of said cylinder in a series surrounding said shaft, a lamp socket on each bracket, a terminal member surrounding the shaft and secured in the end wall of the cylinder, a negative terminal in each terminal member connected with the negative side of lamp sockets in the cylinder in which said terminal member is mounted, a series of segmental terminals

in each terminal member and concentric therewith and each of said segments connected with the positive side of a lamp, a corresponding stationary terminal member surrounding the shaft adjacent the terminal member in the adjacent cylinder, and means for supplying a positive current to said series of positive segmental terminals, whereby the lamps of the entire series of cylinders will be supplied with current from a single source.

9. Pictorial display apparatus, including a shaft, a plurality of individual pictorial cylinders frictionally mounted thereon, each cylinder having two similar end walls, a cylindrical terminal member in each end wall surrounding said shaft, a plurality of radially projecting angle plates, a series of electric lamp sockets, a bracket for mounting each lamp socket and each bracket bent at each end thereof to form an upturned end adapted to be secured upon and to the angle plates on said terminal member, means for supplying electric current to said terminal, and means in said cylinder for conveying current to the lamp.

10. Pictorial display apparatus, including a shaft, a plurality of individual pictorial cylinders mounted thereon so as to be independently revoluble, an electric lamp, and a neon tube mounted in connection with each cylinder so as to revolve therewith, and means in each cylinder registering with corresponding means in adjacent cylinders for supplying electricity to said lamps and neon tubes in said plurality of cylinders.

11. Pictorial display apparatus including a shaft, a plurality of individual pictorial cylinders mounted thereon so as to be independently revolved and each cylinder having a plurality of pictorial faces, an electric lamp, and a neon tube for each pictorial face being mounted in each of said cylinders and electric terminals in each end of each cylinder electrically connected with said electric lamps and neon tubes and registering with and engaging corresponding terminals in adjacent cylinders for supplying electric current thereto.

12. Pictorial display apparatus including a shaft, a plurality of individual pictorial cylinders frictionally mounted thereon, so as to revolve therewith or be independently revolved as desired, each cylinder having a plurality of pictorial faces in the periphery thereof, and a neon tube construction mounted in each pictorial face of each cylinder, electric lamps mounted in each cylinder, one for each pictorial face, and electric terminals in each end of each cylinder electrically connected with said lamps and neon tubes and registering with and engaging corresponding terminals in adjacent cylinders for supplying current to said neon tubes.

13. Pictorial display apparatus including

a shaft, a plurality of individual pictorial cylinders mounted thereon so as to be independently revolved, neon tubes mounted in each cylinder and electric terminals in each end of each cylinder electrically connected with said neon tubes and registering with and engaging corresponding terminals in adjacent cylinders for supplying current to said neon tubes.

10 In witness whereof, I have hereunto affixed
my signature.
